(57) **CLAIM**

The ornamental design for a wall dock for tablet, as shown and described.

DESCRIPTION

FIG. 1 is a front perspective view of a wall dock for tablet showing my new design;

FIG. 2 is a rear perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof;

FIG. 8 is a bottom plan view thereof; and,

FIG. 9 is a front elevation view thereof with a tablet device mounted therein.

The dot-dash broken lines define the boundary of the claim, which extends to the boundary but does not include the boundary. The broken lines showing the mounted tablet device in FIG. 9 depict environment only and form no part of the claim. All other broken lines in the drawings depict portions of the wall dock for tablet that form no part of the claimed design.
